CLAIM

The ornamental design for a grommet and handle assembly for handbag, as shown and described.

DESCRIPTION

FIG. 1 is a front perspective view of a grommet and handle assembly for handbag showing my new design;

FIG. 2 is a front view of the grommet and handle assembly shown in FIG. 1;

FIG. 3 is a rear view of the grommet and handle assembly shown in FIG. 1;

FIG. 4 is a left side view of the grommet and handle assembly shown in FIG. 1;

FIG. 5 is a right side view of the grommet and handle assembly shown in FIG. 1;

FIG. 6 is a top view of the grommet and handle assembly shown in FIG. 1; and,

FIG. 7 is a bottom view of the grommet and handle assembly shown in FIG. 1.

The broken line showing of the handles, rivet, and body of the bag is for illustrative purposes only and forms no part of the claimed design.
